UNITED STATES PATENT OFFICE.

SAMUEL S. DEAN, OF MINGO JUNCTION, OHIO.

FEEDING ATTACHMENT FOR NAIL-PLATE FEEDERS.

SPECIFICATION forming part of Letters Patent No. 288,982, dated November 27, 1883.

Application filed January 11, 1883. Renewed October 5, 1883. (No model.)

To all whom it may concern:

Be it known that I, SAMUEL S. DEAN, a resident of Mingo Junction, in the county of Jefferson and State of Ohio, have invented certain new and useful Improvements in Feeding Attachments for Nail-Plate Feeders; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention relates specially to means for feeding the nail-plate automatically into the cutting-knives of the nail-machine.

In all the nail-plate feeders of which I have any knowledge, the feed-rod holding the nail-plate is pushed forward into the knives by means of clamping-jaws, which take hold of the rod—one jaw on each side—at stated intervals, and with the aid of a rock-lever or cam-movement advance the rod holding the nail-plate forward into the knives until the plate strikes the gage, at which point it holds it until the nail is cut. After the nail is cut off from the plate, the jaws open and move backward on the rod and take a new hold. The barrel of the machine is then withdrawn and the plate turned over and pushed back into the knives. Then the clamping-jaws operate to push the nipper-rod forward until the plate strikes the gage, ready for another nail to be cut. This mode of feeding the nail-plate is very unsatisfactory from the fact that it is unreliable in giving an accurate uniform feed motion to the plate. The clamping-jaws are liable to slip or lose their grip on the rod and not push it forward sufficiently far to insure a cut requisite to make a perfect nail. When any variation in the nail-plate occurs, (such as different thicknesses of the nail-plate being used,) there is a liability of the plate slipping through the fingers on the end of the barrel into the moving knife when the jaws are not in operation, and thus permit the rod to slip through the clamping-jaws sufficient to cause the succeeding cuts being imperfect until the feed motion catches up to its proper place. To overcome these objections and provide an accurate uniform feed is the object of my in-

vention; and to accomplish this I have devised a feed-rod having a rack-plate connected therewith, whereby, by means of a pawl and lever connected with the operating mechanism of the nail-plate feeder, the plate is automatically fed into the cutting-knives.

In the drawings, Figure 1 is a side view of a nail-plate-feeding machine similar to those in general use, showing my improvement attached thereto; Figs. 2 and 3, detail sectional views of the feeding mechanism.

Like letters of reference refer to like parts. The letter A represents the frame of a nail-machine; B, a rock-lever operated by a cam-movement, to which is connected the bracket C, supporting the barrel D. This rock-lever operates to withdraw the barrel from the knives sufficiently far to admit of the plate being turned over without striking the bed-knife.

E is a coupling-rod connected with suitable power for imparting motion, by means of a crank, f, and lever d, to a vertically-sliding rack-plate meshing with a toothed gear around the barrel to rotate the same for the purpose of turning the plate.

F is an arm projecting from the bracket C, of which it preferably forms a part, and serves to support the feed-rod and connecting parts. The outward end a of this arm is turned up at right angles a short distance, and provided with two upright pieces, b b', one on each side, to form a rest or guide for the feed-rod. One of these upright pieces, b', is made preferably of spring-steel, in order that it will maintain a constant pressure on the feed-rod. The other side piece serves as a stop for the lever L operating the pawl M.

G is the feed-rod, consisting of a plain rod of round iron, to which are attached at one end the nail-plate nippers (shown by dotted lines) for holding the nail-plate. The body of this rod, for a short distance, near its upper end, is fitted with a square rod casing or stock, H, having a toothed rack, c, formed in its upper surface. It is also provided with movable collars e e, provided with set-screws s s, to hold the rack in position and adjust the same when needed. When the rod is in position ready to feed the plate, the square stock rests between the upright arms b b', which hold it from turn-

ing while the feed-rod rotates with the movement of the barrel.

K is a thin piece of sheet metal, preferably spring-steel, provided with a central slot 5 lengthwise of the plate, through which is placed a set-screw, h, to secure the plate to the rack. The object of this plate is to form a stop for the feed mechanism by covering up the teeth to a point where it is required to stop the feed.

10 L is a lever pivoted to the arm F.

M is a pawl pivoted to the upper end of the lever, the latter also having an arm, k, hung rigidly on the same pivots, to which is attached a spiral spring, l, to hold the pawl 15 down on the rack. This pawl is capable of being turned back or thrown over its center to permit of the feed-rod being removed to insert another plate.

N is a push-bar pivoted to one end of the 20 lever L, or secured by any well-known adjustable connection, and resting in a suitable bearing on the frame of the barrel-bracket, with the end bearing against the body of the nail-machine or a spring stop or cushion arranged 25 to receive it.

m is a spiral spring to hold the push-rod in tension.

The mode of operation is as follows: The operator first places a nail-plate in the nipper 30 of the feed-rod. He then pushes the end of the feed-rod holding the plate into the barrel of the machine far enough for the plate to be grasped by the fingers of the rod, and presses the body of the rod between the guides b b', 35 provided for holding the same. Then he turns down the pawl onto the rack, and the feeding apparatus is ready for operation. As the barrel of the machine moves forward by means of the rock-lever to present the plate to the 40 knives, the push-bar N engages with the stop or cushion on the body of the nail-machine and causes the lever L to operate the pawl M, resting on the rack c, which forces the feed-rod G forward one or more notches at each 45 successive movement of the feed mechanism. The stop-plate K is capable of being adjusted

lengthwise of the rack to fit into the notches at the proper length to feed a nail-plate, so that when the nail-plate is cut away to the end of the nippers the pawl will strike the end of the stop and cease to advance the feed-rod, thus avoiding injury to the working parts and giving notice to the operator when the plate has been cut away. As the feed-rod is rotated by the barrel, it is obvious that the rod can be made in two sections—one part with the nippers attached and the other provided with a rack-plate—connected together at the ends, so that the portion to which the nippers are attached can rotate, while the other remains stationary. This form of construction I claim as a modification of my invention.

Having described my invention, what I claim, and desire to secure by Letters Patent of the United States, is—

1. In a nail-plate-feeding machine, a feed-rod provided with an adjustable rack-plate, for the purpose—in connection with a pawl and suitable operating mechanism—of feeding the nail-plate accurately into the cutting-knives, 70 substantially as herein shown.

2. In a nail-plate-feeding machine, the feed-rod G, provided with a square-sided casing or stock, H, having a tubular bore for the passage of the rod, and fitted with a rack on the 75 upper side, and movable collars e e, to adjust the same on the rod, in combination with the pawl M, lever L, and rod N, substantially as and for the purpose herein set forth.

3. The combination, with the feed-rod G, 80 having a stock, H, fitted with a rack, of the upright arm b and spring-arm b', for holding the same steady in place, substantially as herein shown.

In testimony that I claim the foregoing as my 85 own I hereby affix my signature in presence of two witnesses.

SAMUEL S. DEAN.
